CONTROL DEVICE

Bernard A. Brown, Carl H. Kindl, and Robert C. Kestle, Dayton, Ohio, assignors to Delco Products Division of General Motors Corporation, Dayton, Ohio, a corporation of Delaware

Application June 4, 1934, Serial No. 728,840

10 Claims. (Cl. 172—279)

This invention relates to improvements in speed-responsive control devices and particularly to such devices especially adapted for use in connection with electric machines.

5 It is among the objects of the present invention to provide a speed-responsive control device of simple structure and design, properly balanced and capable of operating substantially without noise.

10 A further object of the present invention is to provide a unitary structure comprising a speed-responsive control device and an air-circulating device, both these devices being so constructed and arranged as to counterbalance each other.

15 Further objects and advantages of the present invention will be apparent from the following description, reference being had to the accompanying drawings wherein a preferred embodiment of one form of the present invention is clearly shown.

20 In the drawings:

Figure 1 is a perspective view of the automatic speed-responsive switch-actuating mechanism and the air-circulating device for the motor.

25 Figure 2 is a perspective view of the electric switch.

Figure 3 is a group of perspective views of the automatic switch-operating mechanism disassembled.

30 Figure 4 is a fragmentary cross sectional view of the switch and the automatic control mechanism therefor. In this view the control mechanism is shown in normal position.

35 Figure 5 is a view similar to Figure 4, showing the switch-actuating mechanism in active position.

Figure 6 is a view taken substantially along the line 6—6 of Figure 5, showing the member which engages and actuates the switch.

40 Referring to the drawings, the numeral 20 designates a fragment of the rotor of the electric machine which may be of any standard construction and, therefore, needs no detailed illustration or description. This rotor is provided with a shaft 21 by means of which the rotor is rotatably supported in the frame 22 of the motor, only a fragment of which is shown in Figures 4 and 5.

45 Referring particularly to Figures 2, 4 and 5, the stationary contact 23 is adapted to be connected to the stator winding of the motor, not shown. This stationary contact 23 is normally engaged by a movable contact 24, carried by the arm 25, which is pivotally secured to a pin 26 secured in the end frame 22 of the motor. A 50 spring 28, interposed between the arm 25 and the

frame 22 of the motor, yieldably urges the arm 25 so that its contact 24 is moved out of engagement with the stationary contact 23. On the arm 25 there are provided rubbing blocks 30 adapted to be engaged by a switch actuating sleeve 31, made of insulating material, which sleeve is slidably carried upon the rotor shaft 21 and is urged against the rubbing blocks 30 by a spring 33, interposed between a bracket 34 attached to shaft 21, and the switch actuator 31. 5 Spring 33 exerts sufficient pressure upon arm 25 through actuator sleeve 31 to overcome the effect of spring 28 upon said arm so that normally spring 33 maintains the arm 25 in a position as shown in Figure 4, in which position the contact 15 24 on arm 25 engages stationary contact 23, thus completing a circuit to the stator winding, not shown.

20 Bracket 34 has a tubular hub portion 40 fitting upon the shaft 21 so that said bracket is rotatable therewith. As shown in Figure 3, this bracket comprises a plurality of radially extending arms 42, 43, 44 and 45. Arm 42 of bracket 34 is on one side of a plane passing through the axis of the shaft 21, while arms 43, 44 and 45 25 are on the opposite side of said plane. Arm 42 has a portion 46 formed at right angles to the arm 42, said portion 46 having two angularly shaped, spaced tangs 47 and 48, each providing a V-shaped pocket 49 in alignment, but spaced as 30 shown in Figures 1 and 3.

25 The member of the automatic control mechanism which is responsive to centrifugal force for purposes of operating the switch actuator 31 is designated by the numeral 50. This member has 35 a plurality of tangs, two of which, numbered 51 and 52, extend inwardly toward each other from oppositely disposed arm portions 53 and 54 respectively. These tangs 51 and 52 pivotally seat into the V-shaped pockets 49 formed in the tangs 40 47 and 48 of bracket arm 42. The arms 53 and 54 of the member 50, which member may be termed the governor weight for the purposes of description, extend toward the axis of the shaft 21, the arms being located on opposite sides of 45 the center of the shaft, as shown in Figure 1. At the free ends of these arms inwardly extending flanges 55 are provided, for purposes to be described. Member 50 has two outwardly extending arms 56 and 57 to which are secured springs 50 60 which yieldably urge the governor weight into normal position, only one of the springs being shown in Figure 1, the other in the Figure 5. Another downwardly extending tang 61 on the member 50 extends into a longitudinal groove 55

in the switch-actuating member 31 normally engaging the inner end wall of said groove.

A resilient member 10 is secured to the arm 42 by a rivet 18 passing through the openings 71 and 72 on the member 10 and bracket 34 respectively. This rivet has an enlarged head about which one end of spring 33 fits so that dislodgment or disalignment of the spring is prevented. A plurality of flexible tongues are provided on member 10, the first, designated by the numeral 15, being engaged by and forming a cushioning element for the governor weight 50 when it is urged into a normal position under the effect of springs 60. Figure 4 clearly illustrates how the member 50 engages this flexible tongue 15 when in normal position. Two spaced flexible tongues 16 of member 10 engage the lower edges of tangs 51 and 52 of the governor weight resiliently holding them in pivotal engagement with the V-shaped pocket 48 of tangs 47 and 48 of the bracket 42. Thus tongues 16 normally yieldably maintain the governor weight in hinged engagement with the bracket arm 42. Two other flexible tongues 11 are provided on the member 10 which, when said member is attached to bracket arm 42, are normally spaced from said arm so that when the governor weight is thrown into active position, as shown in Figure 5, due to centrifugal force, flanges 53 of arms 53 and 54 of said governor weight, engage said flexible tongues 11, whereby this movement of the weight is cushioned to prevent impact noises which would occur if the weight were permitted to engage solid parts.

Arms 43 and 45 of the bracket 34 each have an angular portion 143 and 145, and arm 44 has a similar angular portion on each of its sides, these being designated by numerals 144 and 146 respectively. All of these angular portions provide vanes which set air in motion for the purpose of cooling the motor. The arms 43, 44 and 45, plus their vanes 143, 144, 145 and 146 counterbalance the arm 42 of the bracket 34 and its automatic control mechanism. In order to provide a substantially perfect balance, certain of the arms have openings 80 while others are provided with counterbalancing weights 81, as needed.

The device functions in the following manner: when the motor is at rest the control mechanism 50 will assume the position as shown in Figure 4 in which contact 24 engages with contact 23 and the switch actuating member 31 is exerting a pressure upon the rubbing blocks 30 of arm 25 due to the effect of spring 33. When the main 55 circuit through the motor is closed and it starts to rotate the mechanism will remain in normal position until a predetermined speed of the rotor 20 is attained at which time the governor weight 50, due to centrifugal force, will move about its 60 pivotal tangs 51 and 52 in a counterclockwise direction as regards Figures 1, 4 and 5, until it has assumed a position as shown in Figure 5. Moving in counterclockwise direction against the spring 60, interposed between the weight 50 and the 65 vanes 143 and 145 of the arms 43 and 45, causes tang 61, which engages the switch actuator 31, to move said actuator toward the right upon shaft 21, as regards Figures 1, 4 and 5, against the effect of spring 33. This permits spring 28 to move arm 70 75 so that its contact 24 is disengaged from contact 23 thus breaking the circuit through the stator winding, not shown. As the weight is moved counterclockwise, such movement sometime occurring rather suddenly, the portions 55 thereof engage with the flexible tongues 11 on

the resilient member 10, thus this movement of the weight is combined and checked without any undue noises. As the rotor speed is reduced to a predetermined degree the spring 60 will overcome the effect of the centrifugal force and move the weight 50 clockwise about its pivotal support and as it approaches its normal position, said weight will engage the flexible tongue 15 of the resilient member 10, thus the return movement of the weight 50 is cushioned and impact noise is substantially eliminated.

The flexible tongues 16 yieldably urge the tangs 51 and 52 into the pivotal pockets 49 of the bracket tang portions 47 and 48, providing means which greatly facilitate quiet operation of the device and permitting sufficient play between moving parts without affecting the operation thereof.

From the foregoing it may be seen that applicants have provided an automatic control mechanism for an electric motor, of simple structure and design, for practically all of the parts are made from stampings. The details of the construction permit easy assembly for substantially all moving parts of the entire mechanism are maintained in assembled position by resilient means which, as has been mentioned before, tend to quiet operation inasmuch as free play may be had between the moving parts without permitting disengagement.

While the form of embodiment of the present invention as herein disclosed constitutes a preferred form, it is to be understood that other forms might be adopted, all coming within the scope of the claims which follow.

What is claimed is as follows:

1. A speed-responsive control device comprising in combination, a rotatable member; speed-responsive means carried by said member only on one side of its axis and having an axis of movement substantially perpendicular to the axis of the rotatable member; means adapted to be actuated by said speed-responsive means; air-circulating means secured to the rotatable member on the side of its axis opposite the speed-responsive means, said air-circulating means also counterbalancing said speed-responsive means.

2. A speed-responsive control device comprising in combination, a rotatable member; speed-responsive means adapted to move about a pivot and carried by said member only on one side of its axis the axis of said pivot being substantially perpendicular to the axis of said member; means adapted to be actuated by said speed-responsive means; fan blades secured to the rotatable member on the side of its axis opposite the speed-responsive means, said fan blades circulating air about the rotatable member and providing counterbalancing means for the speed-responsive means.

3. A speed-responsive control device comprising in combination, a rotatable member; a centrifugal governor; means adapted to be actuated by said governor; and air-circulating means secured to the rotatable member, said air circulating means supporting the governor on one side of the axis of the rotatable member and providing counterbalancing means for said governor on the opposite side of said members' axis.

4. A speed-responsive control device comprising in combination, a rotatable member; means for circulating air about the rotatable member; a centrifugal governor; means adapted to be actuated by said governor; a bracket attached to said member, having radially diverging arms, one of which supports the governor on one side of the

- axis of the rotatable member, the other providing counterbalances for the governor and supporting said means for circulating air about the rotatable member.
5. A speed-responsive control device comprising in combination, a rotatable member; a centrifugal governor having a speed responsive element; means adapted to be actuated by said governor, and a bracket attached to said member, having radially diverging arms, one of which pivotally supports the speed-responsive element of the governor on one side of the axis of the rotatable member, the others providing counterbalances for the governor and having angular portions forming air-circulating fans.
10. A speed-responsive control device comprising in combination, a rotatable member; a governor having a speed-responsive element pivotally engaging said rotatable member; means adapted to be actuated by said governor; and a resilient member yieldably holding said speed-responsive element in pivotal engagement with the rotatable member and providing cushioning stops for the speed-responsive element of the governor.
15. A speed-responsive control device comprising in combination, a rotatable member; a governor having a speed-responsive element pivotally engaging said rotatable member; means adapted to be actuated by said governor; and a member having a plurality of resilient portions certain of which yieldably hold the speed-responsive element of the governor in pivotal engagement with the rotatable member, others providing resilient stops for the speed-responsive means at each end of its travel.
20. A speed-responsive control device comprising in combination, a rotatable member; a supporting member attached thereto; a governor having a speed-responsive element pivotally engaging said supporting member; means adapted to be actuated by the governor; and means attached to the supporting member and providing a plurality of flexible tangs, certain of which yieldably maintain the speed-responsive element of the governor in pivotal engagement with the supporting member, others providing resilient stops adapted to be engaged by the speed-responsive element at each end of its travel.
25. A speed-responsive control device comprising in combination, a rotatable member; a bracket attached to said member and having radially diverging arms; a governor having a speed-responsive element pivotally engaging one of said arms; means adapted to be actuated by said governor; means attached to the bracket arm supporting the speed-responsive element of the governor, said means having a plurality of flexible tongues, one of which yieldably maintains the speed-responsive element in pivotal engagement with the bracket arm, the others providing resilient cushioning stops for said element at each end of its travel; air-circulating means provided by the bracket arms on the side of the rotatable members' axis opposite the governor supporting arm, said means also providing counterbalances for said governor; and resilient means connected between the speed-responsive element and certain of the air-circulating means for yieldably urging said element into normal position against one of the cushioning stops.
30. A speed-responsive control device comprising, in combination, a rotatable member; a governor having a speed-responsive element movable with respect to the rotatable member; means actuated by the governor upon movement thereof; a bracket having arms, one of which arms supports the speed-responsive element, and another of which provides an air circulating fan; and resilient means biasing the speed-responsive element in one direction, said resilient means being anchored at one end to the air circulating fan.
